UNITED STATES PATENT OFFICE.

FREDERICK E. MARTIN, OF BERKELEY, CALIFORNIA, ASSIGNOR TO MARTIN AIR DOG COMPANY, OF SAN FRANCISCO, CALIFORNIA, A CORPORATION OF CALIFORNIA.

TAPERING MECHANISM.

Application filed May 29, 1924. Serial No. 716,744.

To all whom it may concern:

Be it known that FREDERICK E. MARTIN, citizen of the United States, residing at Berkeley, in the county of Alameda and State of California, has invented certain new and useful Improvements in Tapering Mechanism, of which the following is a specification.

This invention relates to improvements in means for tapering logs on saw mill carriages, and is particularly directed to a motor mechanism having a definite range of travel, made up of a series of independent limited steps, with such motor mechanism arranged in such definite relation to the knee as to provide for the maximum range of travel without interference with or by the usual mill equipment. The control of the motor mechanism is so arranged that the independent steps of motor travel may be successively or selectively controlled to cause the knee to move for each step in succession throughout the range of travel, or for any one of said steps of movement. Furthermore, in the preferred form of the invention, the motor mechanism is without direct connection with the knee, and means are provided, whereby the relative initial position of the knee and motor mechanism in so far as the operative contact between these parts is concerned may be adjusted, to insure an accurate initial position of the knee, thus compensating for wear of the parts.

In my co-pending application, filed November 19, 1923, Serial Number 675,706, there is described motor mechanism for tapering a knee, having a definite range of travel, made up of a series of successive steps, with the motor having direct connection with the knee, means being provided for operating the motor throughout the series of steps in succession, with each motor step defining a taper position of the knee. In this particular construction, the maximum range of travel of the motor, to insure the knee moving from the minimum to the maximum taper position, necessitated such a length of motor that when the motor was connected to the knee, as described in such application, the projection of the motor interfered to some extent with certain necessary mill equipment in certain positions

of the knee, and hence this construction while admirably adapted under some conditions was not equally serviceable in all. 55

Furthermore, in the noted application, the motor mechanism had its operative part directly connected with the knee, and hence it was difficult to adjust the knee to an exact position in compensating for wear, as the motor connection prevented such adjustment in a commercial practical way. 60

The present invention provides a motor mechanism which is so associated with the knee that the full maximum range of travel of the knee for taper adjustment is permitted, while the overhang or projection of the motor beyond the knee is so limited that the full movement of the knee is permitted 70 without obstruction from necessary equipment in the saw mill. 65

The present invention also provides for a contact cooperation between the operative part of the motor mechanism and a member carried by the knee, to cause the knee to respond to the operation of the motor. The motor operating part is thus wholly free of all direct connection with the knee, and the member carried by the knee 80 to be engaged by the motor in operation is arranged for convenient adjustment, to thereby vary the relation of the knee and operating part of the motor mechanism. Thus, the knee may be accurately set in 85 a predetermined position and all wear of parts compensated for in maintaining this predetermined set of the knee in a simple and convenient manner. 75

In the application referred to, the motor mechanism was arranged for pneumatic control and the respective motor steps of movement were designed for successive operation. While this is advantageous in handling some types of logs, it has been found that to conserve power in handling other types of logs the motor mechanism should be capable of being operated selectively with respect to any desired step of movement without the necessity of operating such motor mechanism through any preceding steps of movement. 90

Therefore, the present invention contemplates the provision of a motor, wherein any particular step or steps of movement may 105 be selectively brought into play without in

any way affecting or influencing any preceding steps of movement.

In taper mechanisms as heretofore provided, the step by step movement, whether by a motor or by the ordinary dog and segment, the taper movement of the knee was in exact accord with the motor movement or with the distance between teeth or notches of the control. Under these conditions, the 10 taper of a log was limited in the number of possible taper movements to the number of different taper steps or of teeth or notches. It is however, important that a greater range of taper be permitted a log than is ordinarily possible, owing to the limited space 15 permitted the taper control mechanism with a motor mechanism having normally spaced steps, or one involving teeth and notches.

In the present invention therefore, it has 20 been found desirable to have the motor steps of movement bear a definite predetermined relation in taper measurement, say for example, one and one-half, four and one-half, seven and one-half, and ten and one-half 25 inches taper measurements. With two knees provided with a motor mechanism having the successive steps of movement as noted, the taper possibilities of the log can be materially increased over the usual construction. For example, desiring to taper a log 30 with a three inch taper measurement, one of the knees will be adjusted through the motor mechanism to the second step, moving the log at that end four and one-half inches, 35 while the other of the knees will be adjusted to the first step, moving the log at that end one and one-half inches. Thus the effective taper will be the difference between the one one-half movement of one knee, and the 40 four and one-half movement of the other knee, or three inches, and from this cited instance, it will be apparent that with the steps of the motor mechanism arranged as described, a materially increased variety of 45 taper positions of the log is possible as compared with previous taper mechanisms.

The invention also contemplates what may 50 be termed a reverse motor mechanism, which operating under pressure is effective to return the knee to normal position, or to any position determined by the set of the motor mechanism, and also effective in holding the knee, or rather the member thereof engaged by the motor mechanism in contact with 55 the operative end of the motor mechanism under all working conditions, to insure that the movement of the knee by the motor mechanism will be exactly as effective as if directly connected.

60 In the drawings:

Figure 1 is a diagrammatic plan view illustrating the invention applied to a saw mill carriage.

Figure 2 is a side elevation of a knee and 65 head block with the invention applied.

Figure 3 is a front end view of the same.

Figure 4 is a central longitudinal section through one of the motors and knee.

Figure 5 is a detail view of a group of 70 control valves.

Figure 6 is a diagrammatic view of one of the composite cylinders when the pistons are in normal position.

Figure 7 is a diagrammatic view of one of the composite cylinders showing the position of the pistons when the control is actuated to obtain the first taper position. 75

Figures 8, 9, and 10, are similar views, showing the position of the pistons when the control is actuated to obtain respectively the 80 second, third, and fourth taper positions of the pistons.

Figure 11 is a diagram illustrating the position of the knees when making a standard taper, or when taper measurements of 85 a different variety from the standard are desired, the light dotted lines showing the log position when making a standard taper, and the heavy dotted lines representing the taper measurements of a different variety 90 from the standard desired.

Figure 12 is a detail view of the slide for supporting the composite motor.

Figure 13 is a detail perspective view 95 showing the adjusting means between the knee and the motor.

Figure 14 is a sectional view, partly in elevation, of a taper arrangement according to the preferred construction designed particularly for a rack-and-pinion set works 100

In the drawings, particularly Figures 1 to 13, a saw mill carriage is conventionally indicated at 1, on which are mounted head blocks 2, formed with guideways 3, to accommodate screws 4 rotated by gears enclosed in a housing 5 and operated from the set shaft 6. There may be several knees and head blocks and therefore a description of one will suffice. 110

The upper surfaces of the side flanges of the head block are formed with guides 7, and a slide 8 of a width equaling that of the head block is formed on the underside with grooves 9 to slidably cooperate with the guides 7, the upper surface at the side edges of the slide having gibbs 10. A rib 12 depends from the central portion of the slide, and is provided with a nut housing 13 to receive a nut 14 cooperating with the screw 4. 115

An integral cylinder section 17 forming part of the motor mechanism, forms part of the slide 8, this cylinder section extending rearwardly from the slide with respect to the knee and is provided near its rear edge with a flange 18. The head of the cylinder, that is, the end toward the knee, is formed with a central opening 19, being otherwise closed. In alignment with the 120

cylinder section 17, is a plurality of cylinder sections designated 20-21 and 22 and fitting on the rear end of the last mentioned cylinder section is a head 23. Tie bolts 24 extend thru the flanges on the rear cylinder section 22 and the flange 18 on the front cylinder section 17, the structure as a whole forming a composite motor cylinder to receive a plurality of pistons 25-26-27 and 28. The piston 25 is composed of several disks 29, with interposed packing, the disks being mounted on the reduced end of a ram rod 30 and locked in position thereon by a nut 31, the forward end of the rod extending through the opening 19.

The pistons 26-27 and 28 are all exactly alike, except as to length, hence I will describe but one in detail. Each piston is hollow, and in its forward end is a cavity 33, to accommodate the nut 31 which secures the disks forming the preceding piston, while the rear end is flanged and has bolted to it a pair of disks 34 with suitable packing therebetween. A bolt extends through the rear end of the piston and is locked in place by a nut 35, which is received in the cavity formed in the forward end of the succeeding piston. The body portion of the piston is of less diameter than the interior diameter of the cylinder section in which it reciprocates, and its periphery is provided with a plurality of ribs 36 which fit in correspondingly shaped notches or recesses 37 formed in an inwardly extending flange 38, at the forward end of the cylinder section. This flange not only affords means in which to form the guides 37, but it also acts on one side to form an abutment to limit the rearward movement of the piston in the preceding cylinder section and its opposite side forms an abutment to limit the forward movement of the piston in the particular cylinder section in which the piston reciprocates. As stated, the three pistons are just alike except as to their length. The rearmost cylinder section is the shortest, and each successive cylinder section in advance thereof is of relatively increased length, each piston from the rear to the front being of increasing length in accordance with the relative lengths of the cylinders, the piston in advance however, being merely a series of discs to permit a stroke equal to the full length of the cylinder section in advance. When the parts are in normal position, or in a state of rest, the proportions are such that the front walls of the three rear pistons terminate just behind the rear wall of the one preceding it, there being just clearance enough to allow each piston to come up against its abutting flange.

The length of the respective cylinder sections and their cooperating pistons as shown, are such as to bring about a definite

and predetermined movement of a knee to make what may be designated standard taper adjustments, the various movements being arranged that two knees may be manipulated to maintain the standard, or such adjustment may be broken up or destroyed to effect taper positions, of a different variety of taper measurements, as will appear later on in this description.

Each knee comprises side walls which are connected at their upper ends by a cross member 40, and at the bottom said walls are connected by a cross member 41, which rides on the upper surface of the flanges of the head block, and when the knee is in normal position said cross member 41 lies adjacent the front edge of the slide 8, as shown in Fig. 4. The sides of the knee depend below the top of the slide and the top of the flanges of the head block, and to the under side of the depending portions are fastened inwardly projecting gibs 42 which engage under the side flanges of the head block and form guideways for the movement of the knee on the slide and head block. In the bottom of the knee are grooves 43, which receive the flanges 10, on the slide, to prevent lateral spreading of the knee, while the depending end flanges on the slide fit in and are guided in grooves 43 formed in the upper surface of the head block.

In the rear portion of the knee is formed a cavity 44, to receive the foremost cylinder section 17, and extending across the knee in advance of the cavity and through elongated openings 45 in the side walls of the knee is a bar 46 of substantial strength and thickness. This bar is provided with flat surfaces so as to fit snugly the walls of the elongated openings, or shims 47 may be inserted in the openings to insure the free end of the ram 30 of the motor engaging the bar in the knee to obtain the desired adjustment.

The bar projects through the elongated openings, and fastening bolts 49 extend through reinforcing flanges 50 and the bar to secure said bar in fixed position. It is essential that the knee be adjusted on the head block so that the free end of the ram will be up against the square surface of the bar to receive the impact, when the motor is operated, and to move the knee the exact predetermined distance by the movement of any one, or any combination of pistons, to insure exactness in the measurement in any tapering operation. To provide for this contingency, the shims or wedges 47 may be inserted in the elongated openings in the sides of the knee, after the bar has been adjusted with reference to the end of the ram, the end securing bolts 49 being inserted and tightened to thereby hold the knee in fixed relation to its motor.

Secured to the flanges at the lower sides of the knee are projecting bars 53, and their

rear ends are connected by a plate 54. While the plate is primarily designed to be used for a mounting for operating mechanism carried by the knee, I also utilize it as a stop 5 to limit the movement of the knee in one direction. The plate 54, which thus underlies the cylinder and is connected to and movable with the knee through the bars 53, is adapted to engage the flange 18 of the 10 cylinder (see Fig. 4) to serve as a limit stop for the knee. Thus in the event of failure of the connection 54 and 55 between the knee and the composite cylinder, the knee is prevented from being thrown off the carriage through the inertia imparted by operation of the pistons when the knee does not meet the log.

Particular attention is directed to the fact that in the construction described, there is 20 no positive connection between the ram, and the knee, with which it cooperates. Hence in the movement of the knee by the motor, flexibility between working parts is provided, thus reducing to a very large extent 25 possibility of binding or wedging of the elements when in operation.

As will appear later on, when fluid pressure is introduced in the composite cylinder, the ram and the knee are driven forwardly to a predetermined selected taper position, limited in each instance by the 30 flanges 38 in the cylinder sections. It is however necessary to provide means for returning the knee to normal position after 35 completion of a tapering operation, and also reduce the shock, incident to the action of the ram when driving the knee to a tapering position.

In the instance shown I provide a pair of 40 cylinders 54 and pistons 55 mounted each side the knee. Each cylinder is pivoted at 56 to a boss on the side of the cylinder section 7, the rods of the pistons 55 operating in said cylinders being pivoted to the knee 45 at 57. These cylinders are disposed so as to equalize the pull on the knees under the action and effect of a constant supply of fluid pressure introduced through the pipes 58. The constant supply of fluid pressure acts 50 on the pistons as to at all times tend to draw the bar and knee up against the ram. Furthermore, when the motor is actuated to 55 drive the knee to a tapering position, the knee, by momentum will move slightly beyond the desired predetermined position, and here again the effect of the constant pressure in the cylinders 54 comes into play. The shock incident to such momentum is readily absorbed, and then the knee is 60 promptly restored to the desired position without in any way placing undue shock and strain on the motor. This is only made possible by reason of the lack of a positive connection between the knee and motor.

65 It follows therefore that the construction

and arrangement of the parts between the set works mechanism and the knee is designed to provide such flexibility as to greatly reduce the strain and shock on the parts, at the same time the knee is brought 70 to an absolute predetermined position to effect the desired taper. The cylinders 54, may each be provided with any appropriate means for absorbing the shock of the piston in the reciprocal movement. This may be in 75 the form of a restricted inlet and outlet opening for the fluid pressure, in proportion to the area of the cylinder to form a vacuum in the movement of the piston, or springs or other cushion mediums may be used as indicated at 54^a in Fig. 2.

The control means for controlling the movement of the knees will be located convenient to the setter.

In the present instance the control is 80 shown as comprising a bank of valves divided into two groups 60 and 61, there being one group for each knee. Each valve is constructed to cooperate with an inlet port 63, an exhaust port 64, and an outlet port 65. 90 All the inlet ports in one group communicate with a manifold 66 supplied with fluid pressure. The outlet port of each valve in group 60, communicates respectively with 95 ports 67-68-69 and 70, in one of the composite cylinders on knee A, while similar communication is had between the outlet ports of the valves in the group 61 with corresponding ports in the composite cylinder 100 on the companion knee B.

In the modified form of the invention shown in Figure 14, the preferred construction is shown as adapted for use in connection with set works which include a rack and pinion for adjusting the knee. Certain 105 mechanical changes are necessary to apply the invention to this type of knee, but the principles of the improvements are maintained.

In these figures 71 indicates the usual set 110 works rack and pinion connection. Extending from and supported on the knee, is a composite cylinder provided with a forwardly projecting housing 16^a. Mounted to reciprocate in the cylinder sections in the 115 composite cylinder are pistons, and projecting from the foremost piston is a ram 30^a which abuts against a rectangular bar 73 mounted in elongated openings 74 in the upper end of a lever 75, pivoted between the 120 side plates of the knee and pivotally connected at its lower end to a link 75', which in turn is pivoted to a lug at 76 on the rack. The elongated openings 74 are provided with 125 shims or wedges and bolts are employed to fasten the parts together after proper adjustment has been made.

While the fluid pressure arrangement is preferred to return the parts to normal position, I may employ a spring 78, for this 130

purpose. It is evident that under certain conditions and on certain rigs, a spring arrangement may be employed to return the parts shown in Figures 1 to 13 to normal position, and that fluid pressure may be employed in connection with the modified form to return the parts to normal position. It is to be also understood that while I have conventionally illustrated two knees in the drawings, additional knees equipped with the invention may be used if desired.

In the operation of the construction shown in Figs. 1 to 13, let it be assumed that the parts are in normal position, as illustrated in Figures 2, 4 and 6; that is, with the bar 46 of the knee up against the end of the ram 30, and the pistons in the composite cylinder in a state of rest, and it is desired to move the knee to the first predetermined selected taper position. Valve *a* in group 60 is operated to admit fluid pressure to the rear end of cylinder section 22 adjacent the head 23 which drives the piston 28 forwardly until its flanged end contacts with the first internal flange 38 which limits its forward predetermined movement, as shown in the diagram in Figure 7, the knee A being advanced to position a log *i* against the knees to make a taper of one and one-half inch as shown in Figure 11. As the pistons are all in alignment, and in substantial contact with each other, when in a state of rest, movement of the rear piston 28 correspondingly advances all the pistons in the composite cylinder, and through the medium of the ram 30 and the contact bar 46, the knee is advanced a distance equal to the distance travelled by the actuated piston. In the sudden forward movement of the ram, slight overrun momentum is imparted to the knee, but this movement is cushioned by the continuous pressure in cylinders 54—54, and by means of this pressure in cylinders 54, the knee is instantly returned to, or may be said to be substantially held in contact with the end of the ram. Thus in the movement of the pistons, the shock on the knee is absorbed.

While provision is made for a taper movement of the knee or knees, as a result of the operation of the rearmost piston, it may be and frequently is desirable to hold the knees in the first taper position as their normal position, as thereby, particularly in handling large logs, the pressure behind the rearmost pistons of the knees acts as a buffer to relieve the blow and strain incident to the logs striking the knees.

If consecutive and further predetermined taper movements of the knee or knees is desired, the successive valves *b*, *c*, and *d*, are operated to admit fluid pressure to the respective cylinder sections, with the result that the pistons 27, 26, and 25, will be advanced by the pressure controlled by the re-

spective valves to advance the knees to the limit of movement permitted by the particular piston or pistons. In this connection, it is to be understood that, as will later appear, the respective knee movements, following operation of the particular pistons, may follow a successive movement of such pistons throughout the series, whereupon the knee taper movement will, for example, be advanced say one and one-half inches, four and one-half inches, seven and one-half inches and ten and one-half inches, but it is of particular importance in the present application to note that the pistons are capable of selective movement, that is, any one piston may be operated to the exclusion of the others. Thus as the stroke of the final piston 25 is, for example, ten and one-half inches, this taper movement of the knee may be secured by progressively operating all of the pistons from the rearmost forward by manipulation of the valves *a*, *b*, *c*, *d*, in succession, though if desired, the ten and one-half inch taper movement of the knee may be instantly obtained by operating valve *d*, and thereby actuating piston 25 to the exclusion of and without affecting the other pistons. This is equally true for the taper movement resulting from any one piston, and it is this selective possibility that renders the construction highly important in the saving of time and the economic use of the pressure fluid.

The construction is such that any one of the desired movements may be selected and made, without disturbing the position of the pistons in rear of the one selected to obtain the predetermined selected position of the knee for a definite taper location. For instance, let it be assumed that a four and one-half inch taper position of the knee be desired. The operator opens valve *b* and the fluid pressure is introduced to the cylinder section 21 and the piston 27, is driven forward against piston 26 which imparts motion to the preceding piston 25, and through the medium of the ram and its co-operating bar the knee is advanced. Now if this position is not sufficient, valves *c* and *d* may be operated and pressure introduced in cylinder section 20, or cylinder section 17 and the respective piston or pistons moved as shown in Figures 9 and 10.

It may here be stated that when the last or an intermediate selection is made, the valves previously operated may be set to exhaust position to return the previously operated piston to normal position, although this is not necessary, it being entirely optional with the operator. If, while the parts are positioned to locate the knee at any of one of the increased taper positions beyond the first, for instance a position resulting from actuation of either of pistons 27, 26 or 25, and a predetermined position of the knee

to produce a less taper on the log, say one and one-half inch, is desired valve *a* will be opened to admit pressure in the rear end of cylinder section 22 adjacent the head 23 and valves *b*, *c* and *d* will be opened to exhaust, and the continuous pressure in cylinders 54 will return the knee, pistons 27, 26 and 25 being driven rearwardly until piston 27 contacts with the piston 28. This would also 10 be true with other cylinder sections and pistons, if a change of position be desired, so that any predetermined taper position of the knee may be obtained, it merely requiring manipulation of the proper valves to obtain 15 the result sought.

It follows from this description of the operation that the operator has a wide range of predetermined selections of taper positions without depending upon the successive 20 movements or actuation of the pistons in rear of those to be operated. In other words, by the construction and arrangement shown, an operator may pick out any one of the pistons and obtain a predetermined selected 25 position, without having first to actuate the pistons for producing a less movement of the knee than that desired.

In practice it is preferable to provide predetermined movements of each knee, equaling distances which may be so sub-divided 30 as to provide increased tapering positions by manipulating both knees. Thus, pistons 28 will advance the knees one and one-half inches; pistons 27 will advance the knee 35 four and one-half inches; pistons 26 will advance the knees, seven and one-half inches; and pistons 25 will advance the knees ten and one-half inches. Now, if either knee 40 is advanced, and the companion knee remains in normal position, one or the other of these predetermined selections will follow. If however the operator finds that a different taper adjustment than that following movement of the pistons in one composite 45 cylinder is desirable, then by manipulating certain of the valves in both groups, an entirely different taper position and measurement is obtainable. For instance, if piston 50 28 in one composite cylinder is actuated, knee B will be advanced one and one-half inches, and if piston 27 in the companion composite cylinder is operated and knee A it controls is advanced four and one-half 55 inches, the distance between the faces of the two knees will be three inches, hence a taper position according to this measurement will result, as indicated by heavy dotted lines *n* in Figure 11. With knee B still remaining in the one and one-half inch 60 position, if piston 26 in the companion composite cylinder is actuated to bring the knee A to the seven and one-half inch taper position, or piston 25 in said cylinder is actuated to bring the knee to the ten and one-half 65 inch taper position, six and nine inch taper

positions respectively will result, as shown by the heavy dotted lines *o* and *p* in Figure 11. Therefore, by the construction described I am enabled to so manipulate the pistons as to bring about predetermined selected 70 standard taper positions of a knee or knees, and by combining the manipulations of the two groups of pistons I am able to select taper positions, the measurements produced thereby, being a division of the standard. 75 In other words, in lieu of a series of predetermined selected positions depending on those following the resultant normal action of the pistons, if advanced distances equaling even inches be desired, I am, by making the movements of the pistons include one and one-half inch measure, enabled to combine the movements of the groups of pistons, and produce another series of movements of different measurements, and thus 80 increase the number of adjustments of the knees for tapering purposes, without unnecessarily increasing the length of the operating means for bringing about the result. 85

When a log is thrust on the carriage, the fluid pressure behind the pistons serves to greatly reduce the shock and strain on the parts. This action is greatly augmented by the independence between the end of the ram and the cooperating cross bar, as the 90 flexibility between these two parts is such that when the knees receive the blow of a log, the jar is transmitted to the pistons, and is promptly absorbed by the cushion, and while the log is settling, this cushion acts 95 immediately to bring the ram back to its exact predetermined position.

In these operations, the major portion of the knee operates on and is supported on the slides 8, while the front end of the knee operates on and is supported on the head blocks. This affords strength and rigidity to the knee structure and yet the knee and slide as a unit can be set by the usual setting mechanism wholly independent of the pistons. Furthermore it will be seen that the construction is such that the sides of the knee are held together at the bottom by the flanges, and the lower cross member prevents lateral spreading, while upward movement of the knee and slide is prevented by the gib 42. Then again the construction and arrangement of the grooves and gibbs between the slide and block are such that the slide is held against lateral movement, and yet an effective guide is formed for the slide on the head block when using the usual setting mechanism. 110 115 120 125

In the operation of the modified form of the invention shown in Figure 14, the control valves are operated in the same way as previously described, but in lieu of the ram acting directly on the knee it acts on the cross bar on the head of the lever and through the pivotal connection of the lever 130

and the link, the knee is adjusted on the head block for tapering purposes. The spring in this instance serves as a knee return motive power, and additionally to maintain the ram in contact with the bar and hold the knee in proper relation with the parts.

Thus while the pistons are in reality successively operated, they do not serve to advance the knee in successive steps, as the selected piston, by operating directly by admitted pressure, is the only one to directly influence the knee. That is to say, the pistons are not, strictly speaking, successively advanced by the piston in its rear contacting with it, as outlined in the described modified form. Thus a substantial predetermined selection of piston movement is secured without depending on the rear neighboring piston moving the one ahead of it.

In the preferred form, it will be seen that the cavity in the knee affords a seat for the reception of the forward end of the composite cylinder, by means of which the overhang of the cylinder is materially reduced. Otherwise, if the movements of the pistons in any one cylinder were arranged to produce all the taper positions herein described, the length of the cylinder would be such that it would overhang the carriage to an extent as to make the construction impractical in certain types of saw mill carriages.

What I claim is:—

35. 1. In a saw mill carriage, a head block, a knee movable thereon for taper purposes, a cylinder carried by and movable with the knee above the head block, a series of pistons operating in the cylinder, said pistons being aligned in the cylinder and operating in the same direction to impart respectively predetermined taper movements to the knee, and means for selectively operating said pistons.

45. 2. In a saw mill carriage, a head block, a knee movable thereon for taper purposes, a motor mechanism including a cylinder carried by and movable with the knee above the head block, a series of wholly independent pistons arranged in the cylinder and each having a predetermined limit of movement, said pistons being arranged in alignment and operative in the same direction to exert a moving pressure on the knee, and means for selectively operating said pistons.

55. 3. In mechanism for setting and tapering a log on a saw mill carriage, a knee, set works, a motor associated with the knee, said motor comprising a plurality of aligned pistons arranged to advance the knee to predetermined tapering positions, and means capable of selection for acting on a predetermined piston or pistons to advance the knee to a corresponding tapering position.

4. In mechanism for setting and tapering a log on a saw mill carriage, a knee, set works, a motor associated with the knee, said motor comprising a plurality of movable elements arranged to advance the knee to predetermined tapering positions, control means capable of advancing a selected element or elements to position the knee for a predetermined selected tapering position, and means independent of the control means for returning the elements and the knee to normal position.

5. In mechanism for setting and tapering a log on a saw mill carriage, a knee, set works, a motor associated with the knee, said motor comprising a plurality of aligned pistons, one of which engages only the knee, and control means capable of selectively actuating any one of or combinations of said pistons to advance the knee to a corresponding predetermined position, and means independent of the control for returning the knee and piston or pistons to normal position.

6. In mechanism for setting and tapering a log on a saw mill carriage, a knee, a head block, a slide on the head block, a motor carried by the slide, said motor comprising a plurality of aligned pistons, one of which is provided with a ram adapted to extend beyond the motor and abut the knee, means to maintain abutting contact of the ram with the knee, and means for controlling the movement of the pistons to advance the knee to a predetermined position.

7. A tapering mechanism for the knee of a saw mill carriage, comprising a motor carried by and movable with the knee and including a series of aligned pistons, each with a predetermined limit of movement, and means to cause the movement of any selected piston to correspondingly move the knee for taper purposes.

8. In mechanism for setting and tapering a log on a saw mill carriage, a knee, a head block, a motor between the knee and head block, said motor having a ram at one end to abut the knee, means capable of being actuated to advance the ram to predetermined selected positions to correspondingly position the knee, and means for maintaining the abutting relation of the ram and knee.

9. In log tapering mechanism for saw mill carriages, including a knee, a head block, a motor for operating the knee relative to the head block, said motor comprising a series of pistons arranged in alignment and each having a limited range of travel, means whereby the linear movement of the pistons or any selected piston may be communicated in like distance to the knee, and fluid pressure control means capable of selectively operating any one of said pistons to impart

to the knee a movement resultant from the travel of the selected piston or pistons.

10. A log tapering mechanism for saw mill carriages, having a head block and a knee movable relative thereto, a motor, including a cylinder carried by the knee and pistons operative within the cylinder, said pistons being free of connection with the knee but capable of exerting pressure thereon in the movement of the pistons or any of them in one direction, means for operating the pistons, and means for exerting a pressure on the knee in opposition to the piston movement, whereby to maintain operative engagement between the pistons and knee in all operative positions of the pistons.

11. In combination with a knee and supporting head block of a saw mill carriage, of a motor mechanism for the knee comprising a cylinder carried by the knee, a series of pistons arranged within and operative in alignment in the cylinder, a fluid pressure means, and mechanism for selectively controlling the fluid pressure means 20 to thereby operate any particular piston or pistons, and means whereby the linear movement of the selected piston or pistons may be communicated in like distance to the knee.

12. In a saw mill carriage having head blocks, knees movable relative thereto, motor mechanism associated with each knee and including a series of pistons aligned in a cylinder and operative in the same direction 35 to move the knee relative to the head block, the movement of the successive pistons in a cylinder being of relatively increasing distances from the rearmost toward the foremost of such pistons, means for operating any one of the pistons, and means for moving each of the knees in opposition to the piston movement thereof to an extent permitted by the selected final active piston of the particular motor, whereby the knees collectively 45 may be moved throughout a taper range aggregating the movement of the pistons in either or both motors or to a range indicated by the difference in movement of the non-similar pistons of the respective motors.

13. In knee tapering mechanism for saw mill carriages having a head block, a knee movable relative thereto, a motor for operating the knee including a cylinder and a plurality of aligned unidirectional pistons having inherently limited and relatively different extents of movement in the cylinder, means for selectively operating any particular piston to the limit of its stroke, and 55 means for imparting to the knee a movement equal in distance to that of the selectively operated piston.

14. Mechanism for tapering a log on a saw mill carriage, including a head block

and a knee movable relative thereto, motor means operative to impart to the knee a range of travel made up of a series of inherently limited movements, and means for controlling the application of said first mentioned means to select the particular limited movement to which the knee is to be subjected.

15. Mechanism for tapering a log on a saw mill carriage, including a head block, a knee, a member interposed between the knee and head block, with such member movable relative to the knee and the knee movable relative to such member, and a motor for tapering the knee, said motor including a cylinder carried by the member with the knee movable relative to the cylinder in taper movement, and a plurality of pistons operating within the cylinder to taper the knee to different distances, said pistons directly operating the knee in taper movement.

16. Mechanism for tapering a log on a saw mill carriage including a head block and a knee movable relative thereto, of a motor for tapering the knee, said motor including a cylinder with which the knee is relatively movable, a plurality of pistons aligned in the cylinder and operable in the same direction to respectively provide a plurality of predetermined taper movements 95 for the knee, a fluid pressure means for operating said pistons, and means for controlling said fluid pressure means to permit selective independent operation of any one of said pistons or substantially simultaneous operation thereof at will.

17. Mechanism for tapering a log on a saw mill carriage, including a head block and a knee movable relative thereto, motor means for taper operation of the knee, said motor means comprising a cylinder and a plurality of aligned independent pistons arranged in said cylinder, each of said pistons having a limited stroke, fluid pressure means, and valve mechanism for controlling said fluid pressure means to selectively operate any one of said pistons or to operate all or any number of said pistons in a substantially simultaneous fluid pressure admission to the pistons.

18. In mechanism for tapering a log on a saw mill carriage, a knee, a plural aligned piston motor wherein each piston has an inherently limited taper producing movement, means for operating the pistons, and yielding means for limiting the movement of the knee under the inertia imparted thereto in the piston operation.

19. In a saw mill carriage, a head block, a knee movable thereon for taper purposes, a cylinder, a series of pistons aligned in the cylinder and selectively operable to impart respectively predetermined taper

movements to the knee, and fluid pressure means for operating the selected piston, said fluid pressure means acting through the selected piston as a buffer for opposing impact on the knee.

20. A saw mill carriage, a head block, a knee movable thereon for taper purposes, a series of aligned elements adapted when moved to impart respectively predetermined movements to the knee, means whereby an operating pressure may be introduced for the selective operation of any one of said elements to thereby operate such element for knee-taper movement and simultaneously provide a buffer for the knee under log impact.

21. A saw mill carriage having a knee movable for taper purposes, a motor including a series of aligned elements wholly independent of the knee and each capable of individually imparting a taper movement to the knee, pressure means capable of selectively operating any one of said elements, and means for urging the knee in opposition to the movement of the elements to maintain operative engagement between the elements and knee at all times.

22. In a saw mill carriage, a knee movable for taper purposes, a motor free of direct connection with the knee and acting under fluid pressure to impart a taper movement to the knee, and yielding pressure means acting to hold the knee in position to be responsive to motor movement, said fluid pressure means and yielding pressure means serving as opposing buffers for the knee.

23. In a saw mill carriage, a buffer mechanism, including an element to directly receive the horizontal impact of the log and movable horizontally independent of the set

works, and a plural piston motor wherein each piston is capable of imparting a predetermined advanced movement to said element, and means whereby a piston or pistons may be operated to advance said element and simultaneously provide a buffer for the movement of the element under log impact.

24. In a log tapering mechanism for saw mill carriages, including a knee formed with a cavity and a transverse bar extending across the cavity, a head block, a motor for operating the knee relative to the head block, said motor comprising a cylinder and a series of pistons arranged in alignment and each piston having a limited range of travel, the forward end of the cylinder being housed in the cavity when the pistons are in normal position, means including an element extending from the foremost piston and cooperating with the transverse bar, whereby the linear movement of the pistons or any selected piston may be communicated in like distance to the knee, and means capable of selectively operating any one of said pistons to impart to the knee a movement resultant from the travel of the selected piston or pistons.

25. In a saw mill carriage, a head block, a knee movable thereon for taper purposes, a cylinder, a series of pistons aligned in the cylinder and selectively operable to impart respectively predetermined taper movements to the knee, fluid pressure means for operating the selected piston, and means between the knee and cylinder to limit the movement of the knee in one direction.

In testimony whereof I affix my signature.

FREDERICK E. MARTIN.
